UNITED STATES PATENT OFFICE.

WALLIS LEIBER, OF MOUNT CARROLL, ILLINOIS.

LIGHTNING-ARRESTER.

1,115,553.

Specification of Letters Patent.

Patented Nov. 3, 1914.

Application filed October 18, 1913. Serial No. 794,849.

To all whom it may concern:

Be it known that I, WALLIS LEIBER, a citizen of the United States, residing at Mount Carroll, county of Carroll, and State of Illinois, have invented certain new and useful Improvements in Lightning-Arresters, of which the following is a specification.

This invention relates to lightning arresters.

10 My object is to provide a simple, easily installed and comparatively inexpensive lightning arrester for use in any connection where a device of that character is needed, but particularly in connection with telephone systems, and to that end, the invention embodies a lightning arrester constructed and combined with circuit connections, whereby the arrester is normally inactive, but when the lightning discharge occurs on the line, the arrester will operate by electromagnetic action to ground the discharge and short circuit the instruments protected by the arrester.

25 The invention embodies, more particularly, an electromagnet in the working circuit, an armature contact subject to said electromagnet but normally unattracted thereby, and improved features and circuit connections whereby the normal action of 30 the working circuit is insufficient to attract the armature, but when the lightning discharge occurs, the abnormal current energizes the electromagnet, attracts the armature, and thereby grounds the working circuit, at the same time cutting out the instruments and forming a shunt around the electromagnet. In consequence, both the electromagnet and the instruments are protected.

40 The invention is designed to permit telephonic conversation during a thunder storm with barely perceptible interruption due to any lightning discharge which may pass along the working circuit.

45 The invention is set forth fully herein-after and the novel features and combinations thereof are recited in the appended claim.

In the accompanying drawings: Figure 1 50 is a side elevation of the arrester with the circuit connections shown diagrammatically; Fig. 2, a plan view; and Fig. 3, a diagram of the circuits as they run through the arrester.

55 The instrument is mounted on a suitable insulating base 1 on which is mounted a bi-

pole electromagnet 2, a double standard 3 having a base 4, and a contact pillar 5. Pivotedly mounted on the double standard 3 is an armature bar or lever 6 carrying armature 7 and it is provided with an adjustable contact screw 8 and is restrained in its upper position by an adjustable stop screw 9 carried by the pillar 5. A coil spring 10 which is adjustably connected to the parts 4 and 1, is also connected to the lever 6 and the tension of this spring may thus be regulated so that under normal conditions the armature lever 6 will be raised and in contact with the stop screw 9. Preferably, a wire bond 11 connects the lever 6 and standard 3 to afford a better electrical connection between these parts. Either the stop screw 9 or the armature lever 6 is provided with an insulating member to prevent any electrical connection between these parts when the instrument is in its normal condition. The contact screw 8 and the pillar 5 are provided with suitable platinum contacts 12 which will prevent melting or burning of the parts when the contact is made at this point.

A combined binding and fastening screw 13 which secures the base 4 to the base 1, is for connection to the working or line wire 14. Another fastening and binding screw 15 which secures the parts 4 and 1 together, is connected by wire 16 to the electromagnet 2. The other terminal of the electromagnet 2 is secured to a binding screw 17 which is 90 on base 1. The binding post 17 is also connected to the local circuit 18 of the subscriber's telephone instrument 19. The base 1 has another binding post 20 which is connected by wire 21 to the pillar 5 or, it may 95 be mounted on said pillar. This binding screw is in circuit with the ground wire 22 and also with the ground wire 23 leading to the instrument 19.

Normally the spring 10 which has been 100 previously adjusted so as to hold the lever 6 against the stop 9, prevents any short circuiting of the working circuit 14 through the ground 22. The subscriber's circuit is then maintained as follows: circuit 14, base 105 4, circuit 16, electromagnet 2, binding post 17 and circuit 18 and to ground by circuits 23 and 22. If a lightning discharge comes in on the circuit 14, the access of current energizes the electromagnet 2 sufficiently to instantly attract armature 7 and cause contact 110 to be made at 12, whereupon the lightning

2
discharge, instead of passing on to the instrument 19, is at once shunted by way of parts 3, 11, 6, 12, 5 and 22 to the ground, thus connecting at the electromagnet 2 and 5 preventing the same from being burnt out. The discharge having passed, the spring 10 immediately restores the parts to normal position and the circuits to normal working condition without appreciable interruption 10 of talking conditions and the arrester enables the telephone to be used with no substantial interruption while a thunder storm is in progress.

If a complete metallic circuit is employed 15 in connection with the telephones, two of the arresters will be used. Both line circuits will be connected to binding post 13 of each arrester and from binding post 17 of each arrester to the telephone. One ground 20 wire only will be used which will be connected to both binding posts 20 of the two arresters.

Having thus described my invention, what I claim as new and desire to secure by 25 Letters Patent, is:—

In a lightning arrester, the combination with a base, of a standard arising therefrom,

an armature bar pivoted intermediate its ends to said standard, a pillar, a stop screw adjustably carried thereby, insulation interposed between the stop screw and the armature bar, an electro-magnet, a contact screw adjustably carried by one end of the armature bar and adapted to strike the pillar when the armature is attracted by the electro-magnet, a working circuit including the electro-magnet, a by-pass or shunt ground circuit which includes the armature bar, the contact screw, and the pillar, and an adjustable retracting spring co-operating with the 40 other end of the armature bar for keeping the armature bar normally retracted and the contact screw disengaged from the pillar, whereby accession of an abnormal current to said electro-magnet causes attraction of 45 the armature and shunting of the current around the electro-magnet to the ground.

In testimony whereof, I hereunto affix my signature in presence of two witnesses.

WALLIS LEIBER.
